US00D839890S

(12) **United States Design Patent** (10) Patent No.: **US D839,890 S**
(45) Date of Patent: ** Feb. 5, 2019

(54) **DISPLAY SCREEN OR A PORTION THEREOF WITH GRAPHICAL USER INTERFACE**

(71) Applicant: **Cox Automotive, Inc.**, Atlanta, GA (US)

(72) Inventors: **Drew Buchter**, Atlanta, GA (US); **Shannon Rowe**, Atlanta, GA (US); **Greg Hearn**, Atlanta, GA (US)

(73) Assignee: **Cox Automotive, Inc.**, Atlanta, GA (US)

(**) Term: **15 Years**

(21) Appl. No.: **29/649,573**

(22) Filed: **May 31, 2018**

Related U.S. Application Data

(62) Division of application No. 29/599,409, filed on Apr. 3, 2017.
